FLOOR POLISHER

Peter W. Lahr, Racine, Wis., assignor, by mesne assignments, to S. C. Johnson & Son, Inc., Racine, Wis., a corporation of Wisconsin

Application June 12, 1948, Serial No. 146,927

Term of patent 14 years

(Cl. D9—2)

To all whom it may concern:

Be it known that I, Peter W. Lahr, a citizen of the United States, residing at Racine, in the county of Racine and State of Wisconsin, have invented a new, original, and ornamental Design for a Floor Polisher, of which the following is a specification, reference being had to the accompanying drawing, forming part thereof.

Figure 1 is a perspective view of a floor polisher, showing my new design, the handle broken off for convenience of illustration.

Figure 2 is a front elevational view of Figure 1 without the handle portion and on a reduced scale.

Figure 3 is a rear elevational view of Figure 2.

Figure 4 is a side elevational view of Figure 1 on a reduced scale.

The side not shown is substantially the same as the one shown.

I claim:

The ornamental design for a floor polisher, as shown and described.

PETER W. LAHR.
